Fig. 9

The diagram illustrates a mechanical assembly. A vertical line on the left is labeled 126. A horizontal line extends from this vertical line to the right. A rectangular component is attached to this horizontal line and is labeled 111. A curved line labeled 112 extends from the top of component 111 to a vertical spring-like structure labeled 53. A horizontal line labeled 124 extends from the right side of component 111. A vertical line labeled 125 extends from the bottom of component 111. A vertical line labeled 28 is positioned below component 111. A horizontal line labeled 127 is located on the far right.

APPARATUS FOR INVESTING DENTAL
CASTING PATTERNS

David W. Phillips, Chicago, Ill.

Application April 29, 1932, Serial No. 608,219

10 Claims. (Cl. 18—5.7)

This invention relates to the preparation of dental castings and particularly to an improved method and apparatus for investing the casting pattern in a manner which will thoroughly dis-
5 tribute a heavy mix of investment over the sur-
face of the pattern, thereby enabling the produc-
tion of very smooth castings.

In my co-pending application, Serial No. 584,089, filed December 31, 1931, I have disclosed
10 a method and apparatus whereby the casting pattern from which the casting is formed is maintained in vibratory condition during the period in which it is being embedded in the mass of investment. As pointed out in this prior ap-
15 plication, the effect of maintaining the pattern under a condition of vibration while it is being introduced into investment, is to effect complete and perfect distribution of investment over the pattern without permitting formation of air
20 pockets between the pattern surfaces and the adjacent body of investment. In accordance with the practice as disclosed in my prior applica-
25 tion, the pattern was arranged to be movably supported above the investment container, means being provided for automatically raising and lowering the pattern relative to the container, there also being provided means for vibrating the pattern during its movement to and from the container.

30 One of the objects of the present invention is to provide improved means for raising and lowering the pattern relative to the investment container.

Another object of the invention is to provide, 35 in combination with means for effecting vibration of the pattern, additional means operating independently of said pattern vibrating means for imparting vibratory movement to the investment container and the body of the investment contained therein.

Another object of the invention is to provide a method of operation and an efficient apparatus whereby excess moisture contained in the investment after the pattern has become embedded 45 therein may be expelled from the mass by the application of pressure thereto, there being provided means for absorbing moisture which has been thus pressed from the investment.

Other objects and advantages of the invention will appear from the following detailed description, which, taken in connection with the accompanying drawings, discloses a preferred embodiment thereof.

Referring to the drawings:

50 Fig. 1 is a side elevational view of the im-

proved apparatus provided for investing a casting pattern;

Fig. 2 is a front elevational view of the investing apparatus;

Fig. 3 is a top plan view of the same;

Fig. 4 is a fragmentary section through the apparatus taken on line 4—4 of Fig. 1, the view showing the cam mechanism provided for raising and lowering the pattern-supporting assembly;

Fig. 5 is a vertical section through the apparatus taken on line 5—5 of Fig. 1, the view showing the switch mechanism which controls the pattern vibrating means;

Fig. 6 is a horizontal section through the apparatus taken on line 6—6 of Fig. 5, the view showing details of the drive motor which operates the lifting cam;

Fig. 7 is a vertical section taken on line 7—7 of Fig. 5, the view showing further details of the drive motor and the switch mechanism which controls the pattern vibrating means;

Fig. 8 is a detail of the manually operated motor wind-up device, the view being taken on line 8—8 of Fig. 7;

Fig. 9 is a detail section through the platform for supporting the investment container and the means for vibrating said platform; and

Fig. 10 is a schematic wiring diagram showing the circuits provided for energizing the vibrators which are associated with the pattern-supporting means and the platform which supports the investment container.

Referring to the drawings and particularly to Figs. 1-3, the numeral 15 designates a base upon which is supported a box-shaped housing indicated generally by the numeral 16 and consisting of side walls 17, end walls 18, and a top wall 19. Both the base 15 and the housing 16 are preferably made of sheet metal, the housing being removably secured to the base by a series of screws 21 which engage brackets 22 carried by the base.

Referring to Figs. 2 and 9, a tubular investment container 22 is adapted to be supported on the top wall of the housing at the forward end thereof, said top wall being struck downwardly to provide a well or cavity for receiving said container, the side walls of this cavity being indicated at 23, the bottom wall thereof being indicated at 24. Container 22 is not supported directly upon bottom wall 24, a floating platform 25 being provided for supporting the lower end thereof, said platform being supported for free movement on wall 24 by means of a

55

depending plug portion 26 which extends from the under face of platform 25 through an opening 27 formed in wall 24. The depending plug portion 26 constitutes the armature of an electrical vibrator, the coil of which is indicated at 28, said coil being wound about a core 29 which is secured by a bracket 31 to front wall 18 of the housing. In the embodiment shown this platform vibrating means is arranged to be operated by alternating current which is supplied to coil 28 through transformer 32 (Fig. 7) which is mounted on the base 15. It will be apparent that when coil 28 is energized the rapid alterations of the current will provide successive attractions and repulsions of core 26, thereby imparting rapid vibrations to platform 25 and the investment container 22 which is supported thereon.

Continuing the reference to Fig. 9, container 22, in accordance with the usual practice, is adapted to receive a mass of investment 33. The lower end of the container is closed by a rubber end cap 34 which affords a water-tight seal. A casting pattern, indicated at 35, is supported in the investment in the usual manner on a sprue 36 which is removably secured in the lower end of a crucible-forming holder 37, the cone-shaped crucible forming portion 38 of which depends into the mass of investment 33 and the supporting rim portion 39 of which is adapted to rest on the upper edge of the container.

In accordance with one of the novel features of my invention, means is provided for applying pressure to the mass of investment 33 after the pattern has become embedded therein, whereby to produce quick initial setting of the mass by expelling water therefrom. To produce this pressure I provide on platform 25 a plunger portion 41 which engages against the under face of rubber cap 34 and which is adapted to be received in the lower end of the investment container 22. It will be apparent that when a downward pressure is applied to the container 22 and the pattern-supporting assembly positioned thereon, plunger 29 and the overlying portion of cap 34 will be forced upwardly into the lower end of the container, thereby compressing the mass of investment and forcing excess water therefrom. In order to quickly remove this water from the investment, holder 37 is formed of water absorbent material such as plaster of Paris, absorbent paper, or the like. An absorbent sprue-holder 55 which is particularly well adapted for this purpose is shown in my co-pending application Serial No. 596,447, filed March 3, 1932. A description of the means provided for producing downward pressure on the investment container will not be given until after the means for raising and lowering the pattern-supporting assembly has been described.

By vibrating the mass of investment which surrounds the pattern I am able to completely distribute the investment over the pattern surface, thereby avoiding the danger of formation of air bubbles or pockets between the pattern surface and the contacting portion of the investment. Also, by compressing the mass of investment to force excess water therefrom I am able to increase the density of the mass and reduce the time required for the initial set. Inasmuch as the compressed investment contains less moisture for unit volume, it has greater crushing strength and also greater ther-

mal expansion. The steps of vibrating the mass of investment, and of compressing the investment to remove water therefrom are, therefore, both important in the successful production of smooth castings. It is to be understood, however, that these steps need not be necessarily used in conjunction with one another, since either one has its effect independently of the other. Vibration, in conjunction with pressure and absorption, expedites the flow of investment about the pattern without causing distortion of the pattern as the investment is compressed, and also promotes absorption of moisture from and condensation of the investment.

Referring to Figs. 1 and 7, the pattern-supporting assembly, which comprises holder 31 and sprue 36, is arranged to be raised and lowered on container 22. To this end said assembly is adapted to be removably supported on the base by means of a tubular arm 42 which is pivotally connected at one end to a hinge 43, the latter in turn being secured to a plate 44 which is supported by vertical frame pieces 45 and 46. As shown in Fig. 7, the top wall 19 of the housing is struck upwardly, as indicated at 47, the upwardly projecting portion being provided with an opening 48 for receiving arm 42. The free end of arm 42 carries a plate 49 which is provided at its opposite sides with spring-pressed clips 51 (Fig. 2) which are provided at their lower ends with hook members 52 which engage under the rim portions 39 of the sprue holder to firmly hold the latter against the under face of plate 49. In order to release the holder from clips 51, it is merely necessary for the operator to press said clips inwardly to swing jaws 52 clear of rim portion 39. When the holder is in clamped position on plate 49 it may be raised and lowered relative to container 22 by merely swinging arm 42 about its point of pivotal connection with hinge 43. The free end of arm 42 carries a vibrator 53 which is bolted to the upper face of plate 49. This vibrator may be of any preferred form and is not shown in detail. In the embodiment shown the vibrator is supplied with current from the transformer 32. One side of the line is conducted to the coils of the vibrator through a wire 54 which is housed within arm 42. The other side of the line is grounded on the frame. Vibrations induced by vibrator 53 are mechanically transmitted through plate 49 and holder 31 to the pattern. As disclosed in my prior application, Serial No. 584,089, I have found that by vibrating the pattern while it is being inserted into the mass of investment I am able to reduce the tendency toward the formation of air pockets between the surface of the pattern and the contacting mass of investment. As pointed out in said prior application, the preferred procedure is to vibrate the pattern down into the investment, to then remove the pattern from the investment while maintaining it in a state of continuous vibration, and finally reinserting the pattern in the investment, after which vibration is discontinued.

The improved means provided for pivoting arm 42 about its point of support on the base to effect raising and lowering of the pattern-supporting assembly relative to the container will now be described, reference being had to Figs. 4-7. This mechanism comprises: a vertically movable lifting member 55 projecting upwardly through an opening 56 formed in top 75

wall 19; a cam 57 mounted on a shaft 58, the latter being supported between a pair of vertical frame plates 59 and 61; a follower arm 62 pivotally supported at 63 to the frame and provided at its free end with a cam roller 64 for engaging the face of cam 57, said arm being also pivotally connected at 65 to lifting member 55; a spring-actuated motor for driving shaft 58, said motor including a main spring 66 mounted on shaft 58 and a train of timing gears, indicated generally at 67; and a manually operable wind-up device 68 for turning shaft 58 against the tension of spring 66.

Any suitable form of spring motor may be employed for turning shaft 58 and cam 57 and this mechanism will therefore only be described in sufficient detail to give an understanding of its operation in connection with cam 57. The main spring 66 is anchored at one end 20 to shaft 58, the opposite end thereof being anchored to a pin 69 carried by the frame. One end of shaft 58 carries a spur gear 71 which meshes with a vertically disposed toothed rack 72, the latter being adapted to be pushed downwardly against the tension of spring 66 by means of an arm 73 which projects through the side wall of the housing and which is provided at its outer end with a hand piece 74. Arm 73 is secured to a vertically disposed channel-shaped bracket 101, slidably supported on a vertically disposed rod 102 which is supported between base 15 and plate 44, the opposite end portions 103 and 104 of said bracket being apertured to receive said rod 102. A forked member 105 is supported on bracket 101 and engages a laterally projecting stud 105 secured to the lower end of rack 72, thereby providing an operative connection between said rack and bracket 101 which carries arm 73. The ratio of the gear wheel 71 to rack 72 is such that one full downward movement of rack 72 will turn shaft 58 and cam 57 through approximately one complete revolution, the direction of turning of said cam 57 during the wind-up operation being in a counter-clockwise direction, viewing Fig. 4. In the position of cam 57, as shown in Fig. 4, rack 72 will be at the end of its up-stroke, which position represents the point at which the spring motor ceases to function.

The timing mechanism which regulates the turning of shaft 58 comprises: a spur wheel 75 carried by shaft 58; a pendulum 76 supported between plates 59 and 61 on a shaft 77; and a series of intermeshing gears 78, 79, 80, 81 and 82 providing connection between spur wheel 75 on shaft 58 and pendulum-supporting shaft 77.

The lower end of pendulum 76 connects through a spring 83 with a weight wheel 84. An adjusting mechanism, indicated generally by the numeral 85, is provided for raising and lowering pendulum 76 to regulate the timing of the gear train. By setting this adjusting mechanism, the time required for rack 72 to be moved upwardly through a complete stroke may be regulated, thereby, in turn, regulating the time required for cam 57 to turn through one operative cycle.

Referring particularly to Fig. 4, cam 57 is so shaped that it will produce the following cycle of movements of the pattern relative to the investment container 22: (1) a very gradual lowering of the pattern into the investment, this being accomplished by the portion 86 of the cam; (2) A gradual removal of the pattern from the investment, this being accomplished by the

portion 87 of the cam, and this operation being followed by a period in which the pattern is held removed from the investment, this latter function being accomplished by portion 88 of the cam; (3) A second lowering of the pattern into the investment, this being effected by the portion 89 of the cam; and finally (4) A second raising and lowering of the pattern which is accomplished by portion 91 of the cam, this last-mentioned operation resulting in the positioning of roller 64 as shown in Fig. 4, in which position the sprue holder 37 rests flush on the top of container 22. This operative cycle of cam 57, which represents slightly less than one complete turn of said cam, is accomplished during one full return stroke of wind-up rack 72, which, as previously stated, is so geared to shaft 58 as to produce exactly the desired amount of turning of cam 57 during its return or up-stroke. This arrangement is particularly convenient since it is merely necessary for the operator to push downwardly on arm 73 to carry rack 72 to the limit of its down stroke, and upon releasing said arm the motor will automatically operate to turn the cam 57 through exactly the portion of a revolution required to accomplish the aforementioned cycle of movements for the pattern.

The upper end of lifting member 55 is provided with a roller 92 which engages against arm 42 to reduce the friction between these parts. When supporting arm 42 is removed from the upper end of lifting member 55, the latter is thrown upwardly to carry cam roller 64 away from cam 57, this being accomplished by a spring 93 which engages against the lower edge of follower member 62. Since arm 42 is ordinarily removed from lifting member 55 when the machine is not in operation, roller 64 will be normally out of contact with cam 57, so that during the wind-up operation the parts 55, 62, 40 and 64 do not follow the movements of said cam.

It will be noted from Fig. 1 that the pattern-supporting arm 42 is off-set upwardly, as indicated at 94. The purpose of providing this off-set is to insure that pattern 35 will be approximately in line with the axis of the main portion of arm 42. It will be noted from Fig. 9 that the container 22 is positioned in a well or cavity in the top wall of the housing and that the pattern, when completely embedded, is positioned fairly near the base of the container. By off-setting arm 42 in the manner shown, the pattern is so supported that it will move along the vertical portion of its arc of swing as it clears the upper edge of container 22. The arrangement thus insures that there will be no likelihood of the pattern striking the upper edge of the container as it is removed from or inserted into the mass of investment.

The means provided for producing downward pressure on the investment container 22 and sprue holder 37 comprises an arm 95 (Fig. 4) which is carried on the upper end of a rod 96, the latter extending through a bearing 97 which is mounted in top wall 19 of the base housing. Rod 96 is urged downwardly by a coil spring 98 which is connected at one end to the lower end of rod 96, the other end thereof being secured to frame plate 46. One end of arm 95 is provided with a finger loop 99 which may be engaged by the operator to raise said arm upwardly against the tension of spring 98. The other end of arm 95 projects laterally from rod 96 a distance sufficient to carry it over supporting arm 42 when the arm is turned to the

position shown in Figs. 1, 3, and 4, in which position it pulls downwardly on arm 42, thereby producing downward pressure on the pattern-supporting assembly and container 22. The downward pressure thus applied to said assembly and container compresses the mass of investment to expel water therefrom in the manner already described.

Means is provided for automatically starting and stopping vibration of the pattern-vibrating means 53 in accordance with the movements of supporting arm 42. Referring to Figs. 5, 6, and 7, a vertically disposed switch control member 107 is slidably supported on rod 102, the laterally bent end portions 108 and 109 of member 107 being apertured to receive said rod 102. A spring switch arm 111 secured to the base 15 is adapted to be engaged by a second switch arm 112 which is secured to member 107. Arms 111 and 112 are connected in circuit with the coils of the pattern vibrating mechanisms 53, so that when brought in contact with one another they complete the circuit to said coils to start vibration of the pattern. Member 107 which carries switch arm 112, is yieldingly connected to bracket 101 by means of a coil spring 113 which is disposed on rod 102 and which engages at its lower end against a collar 114 supported on the portion 104 of bracket 101. A collar 115 is interposed between the portions 104 and 109 of members 101 and 107, respectively. When rack 72 is in the raised position, bracket 101 will also be raised since it is supported from rack 72 by forked member 105. Switch control member 107 will likewise be held in raised position by coil spring 113 which engages a collar 116 which is carried on the under face of the portion 108 of member 107. When the operator presses downwardly on finger piece 74 to effect wind-up of the motor, bracket 101 is moved downwardly and in turn carries switch control member 107 downwardly, the movement of the latter bringing switch arm 112 into engagement with switch arm 111 to complete the circuit to the coils of the vibrating means 53 when finger piece 74 has been moved down sufficiently to complete the wind-up stroke of rack 72. As member 107 reaches the end of its downward stroke it is latched in place by a lever 117 (Fig. 8) which is pivoted at 118 to frame piece 59, the lower end 119 of lever 117 being adapted to engage over a lateral projection 121 carried by the end portion 109 of member 107. Lever 117 is urged in a counter-clockwise direction, viewing Fig. 8, by a spring 122 which bears on an upper edge portion of the lever. As soon as member 107 reaches its lowermost position, lever 117 snaps over projection 121 and holds member 107 in switch-closing position. As rack 72 approaches the end of its active stroke, lever 117 is thrown to release switch control member 107, this being effected by one arm of forked member 105 which moves upwardly against a lug 123 carried by the upper end of lever 117. Upon being thus released, member 107 is snapped upwardly by spring 113 to produce quick opening of switch 111, 112. The circuit to the pattern-vibrating mechanism 53 is thus automatically made and broken in accordance with the movements of the motor wind-up device which in turn controls the movements of supporting arm 42.

In addition to the switch 111, 112 which automatically controls the operation of pattern-vi-

brating means 53, there is provided a manually-controlled switch 124, by means of which the circuit to this mechanism may be controlled independently of switch 111, 112. A second manually controlled switch 125 is provided for opening and closing the circuit to the coil 28 of the platform vibrating mechanism. The relation of these several switches is shown in the wiring diagram of Fig. 10. In this figure the opposite sides of the main line supply circuit are indicated by the wires 126 and 127. The circuits for the pattern vibrating mechanism 53 and the coil 28 of the platform vibrating mechanism are independent of one another, as shown, the former being controlled either by the automatic switch mechanism 111, 112 or the manually-controlled switch 124, and the latter being controlled exclusively by switch 125. If preferred, the circuit arrangement might be such as to also provide for automatic control of the platform vibrating means in accordance with the movements of pattern-supporting arm 42.

It is believed that a brief statement of the operation will aid to a clearer understanding of the invention. Assuming that the pattern-supporting arm 42 is swung upwardly to inactive position, the operator secures sprue holder 37 between clips 51 and places the investment container 22, into which the desired amount of investment has been preliminarily introduced, on platform 25. The thickness of rubber end cap 34 is such that until downward pressure is applied to container 22 it will remain flush across the lower end of said container. The spring motor is then wound up by pushing downwardly on finger-piece 74 which carries switch arm 112 into contact with switch arm 111 to complete the circuit to the pattern-vibrating mechanism 53. This wind-up operation also pivots cam 57 (Fig. 4) in a counter-clockwise direction through nearly one complete revolution to position the leading edge of the portion 86 of said cam below roller 64. Having preliminarily positioned the parts, the operator lowers supporting arm 42 onto lifting member 55 and at the same time removes his finger from finger-piece 74, thereby releasing the wind-up mechanism and starting operation of the actuating motor. The weight of arm 42 and the pattern-supporting assembly carried thereby holds cam roller 64 against the face of cam 57, causing said roller to follow the surface of cam 57, thereby producing successive up-and-down movements of arm 42.

When the sprue holder finally comes to rest on the top of container 22, switch control member 107 (Fig. 7) is automatically released and opens the circuit to the pattern-vibrating mechanism 53. Vibration of the supporting platform 25 may be continued and discontinued as desired by operation of switch 125. When the sprue holder finally becomes seated on the investment container, the operator may quickly swing arm 95 over supporting arm 42 to produce downward pressure on the latter, which in turn causes downward pressure on the investment container, thereby forcing the plunger portion 41 of platform 25 upwardly against cap 34. The compression of the investment thus produced expels water from the investment and this is absorbed by the holder 37 to produce quick initial setting of the mass. During the period in which pressure is applied to the mass, vibration of either the pattern or the mass of investment, or both, may be continued and discontinued as desired by properly manipulating control switches 124 75

and 125. If preferred, the operator may dispense with the use of pressure and absorption, in which case it is, of course, still possible to use the vibrating mechanisms by properly positioning switches 124 and 125. Also, if desired, the operator may dispense with the use of pressure, and rely solely upon the absorptive capacity of the sprue holder as a means for extracting water from the investment to give quick initial setting. After the investing operation has been completed the pattern-supporting assembly is released by compressing clips 54, whereupon arm 42 may be swung upwardly to allow the investment container and the pattern-supporting assembly to be removed from the base.

The foregoing detailed description has been given for clearness of understanding only, and no unnecessary limitations should be understood therefrom, but the appended claims should be construed as broadly as permissible in view of the prior art.

What I regard as new and desire to secure by Letters Patent is:

1. Apparatus for investing a casting pattern comprising: a base having a platform for receiving an investment container; an arm pivotally supported at one end on the base; means mounted on the free end of said arm for engaging and holding a pattern-supporting assembly; and means for moving said arm about its point of pivotal support, whereby to raise and lower said assembly relative to the container, said means including a vertically movable lifting member positioned to engage said arm intermediate the ends thereof, a motor, a cam adapted to be driven by said motor, and a follower member affording operative connection between said cam and said lifting member.

2. Apparatus for investing a casting pattern comprising: a base having a platform for receiving an investment container; an arm pivotally supported at one end on the base; means mounted on the free end of said arm for engaging and holding a pattern-supporting assembly; and means for moving said arm about its point of pivotal support, whereby to raise and lower said assembly relative to the container, said means including a vertically movable lifting member positioned to engage said arm intermediate the ends thereof, a motor, a cam adapted to be driven by said motor, a follower member affording operative connection between said cam and the lifting member, and a spring for holding said follower member away from the cam when said arm is removed from the lifting member.

3. Apparatus for investing a casting pattern comprising: a base having a platform for receiving an investment container; an arm pivotally supported at one end on the base; means mounted on the free end of said arm for engaging and holding a pattern-supporting assembly; and means for moving said arm about its point of pivotal support, whereby to raise and lower said assembly relative to the container, said means including a vertically movable lifting member positioned to engage said arm intermediate the ends thereof, a spring-actuated motor including a manually-operable wind-up device, a cam adapted to be driven by said motor, and a follower member affording operative connection between said cam and the lifting member.

4. Apparatus for investing a casting pattern comprising: a base having a platform for receiv-

ing an investment container; an arm pivotally supported at one end on the base; means mounted on the free end of said arm for engaging and holding a pattern supporting assembly; means, including a spring-actuated motor and a manually-operable wind-up device, for moving said arm about its point of pivotal support, whereby to raise and lower said assembly relative to the container; and electrically operated means mounted on said arm for imparting vibratory movement to the pattern, said means including an energizing circuit having a switch adapted to be closed by movement of said wind-up device to actuating position, and means for automatically opening said switch when said wind-up device has returned to inoperative position.

5. Apparatus for investing a casting pattern comprising: a base having a platform movably supported thereon and adapted to receive an investment container; a movable support mounted on the base for engaging and holding a pattern-supporting assembly; means for moving said support to carry the pattern to and from embedded position in the container; and means associated with said platform for imparting vibratory movement through the latter to the container supported thereon.

6. Apparatus for investing a casting pattern comprising a base having a platform movably supported thereon and adapted to receive an investment container; a movable support mounted on the base for engaging and holding a pattern-supporting assembly; means for moving said support to carry the pattern to and from embedded position in the container; means carried by said support for imparting vibratory movement to the pattern; and means associated with said platform for imparting vibratory movement through the latter to the container supported thereon.

7. Apparatus for investing a casting pattern comprising: a base having a platform movably supported thereon and adapted to receive an investment container; an arm pivotally supported at one end on the base; means mounted on the free end of said arm for receiving and holding a pattern-supporting assembly; means for moving said arm about its point of pivotal support, whereby to raise and lower said assembly relative to the container; and means associated with said platform for imparting vibratory movement through the latter to the container supported thereon.

8. Apparatus for investing a casting pattern comprising: a base, including a supporting platform having a plunger portion projecting upwardly from the surface thereof; an investment container adapted to be positioned on said platform, said container being open at its upper end, the lower end thereof being closed by an elastic cap adapted to engage over the plunger portion of said platform; a pattern-supporting sprue and a holder therefor, said holder being formed of an absorbent material; a movable support mounted on the base for engaging and holding said sprue holder; means for moving said support to carry the pattern to and from embedded position in the container; and means for applying downward pressure to the container after the pattern has become embedded therein, whereby to expel moisture from the mass of investment by forcing the plunger portion of said platform and the overlying portion of said cap upwardly into the container.

9. Apparatus for investing a casting pattern comprising: a base provided with a platform for supporting an investment container; an arm pivotally supported at one end on the base; and means carried by the free end of said arm for engaging and holding a pattern-supporting assembly, the free end of said arm being off-set upwardly to permit mounting of the pattern in axial alignment with the main portion of said arm, and said platform being arranged to support the container in such position that the upper edge thereof lies approximately in the vertical portion of the arc of swing of the pattern.
10. Apparatus for investing a casting pattern comprising: a base having a platform for receiving an investment container; an arm pivotally

supported at one end on the base; means mounted on the free end of said arm for engaging and holding a pattern-supporting assembly; and means for moving said arm about its point of pivotal support, whereby to raise and lower said assembly relative to the container, said means including a spring-actuated motor having a manually-operable wind-up device, a lifting cam, and means affording driving connection between said cam and the motor and motor wind-up device, said last mentioned means being arranged to move the cam to position for holding the assembly in elevated position when said wind-up device has completed the wind-up movement.

DAVID W. PHILLIPS.
